UNITED STATES PATENT OFFICE

LEE B. GREEN, OF LAKewood, OHIO, ASSIGNOR TO THE GLOBE MACHINE & STAMPING COMPANY, OF CLEVELAND, OHIO, A CORPORATION OF OHIO

DESIGN FOR A COMBINED WASHING MACHINE CASING AND SUPPORT THEREFOR

Application filed May 2, 1931. Serial No. 39,688. Term of patent 7 years.

To all whom it may concern:

Be it known that I, LEE B. GREEN, a citizen of the United States, residing at Lakewood, in the county of Cuyahoga and State of Ohio, have invented a new, original, and ornamental Design for a Combined Washing Machine Casing and Support Therefor, of which the following is a specification, reference being had to the accompanying drawings, forming part thereof.

In the drawings:

Fig. 1 is a side elevation of a combined washing machine casing and support therefor, showing my new design.

Fig. 2 is an end elevation of the same, taken from the right hand side of Fig. 1.

I claim:

The ornamental design for a combined washing machine casing and support therefor, substantially as shown.

LEE B. GREEN.
